TELESCOPE SIGHT MOUNTING

Frederick A. Kuhn, Meriden, Conn., assignor to
 The Lyman Gun Sight Corp., Middlefield,
 Conn., a corporation of Connecticut

Application November 9, 1932, Serial No. 641,848

13 Claims. (Cl. 33—50)

My invention relates to a telescope sight mounting and in certain aspects to a mounting for a hunting type of telescope sight. Hunting types of telescopes and the mounts in which they are supported, especially those intended for use on high power rifles, are required to withstand considerable shock owing to the heavy recoil of these rifles and a great deal of effort has been expended in the art in an endeavor to produce telescopes and mounts having sufficient strength and rigidity to withstand this shock without becoming loosened or otherwise disturbed during the firing of the rifles. The usual mount is provided with a plate which is pinned, screwed and sometimes soldered to the receiver of the rifle and serves as a support for the base of the mount, the latter being removably attached to the plate and having clamping rings in which the telescope sight is secured. Provision is usually made for adjusting the telescope laterally with respect to the base and it has also been proposed to adjust the telescope in a vertical direction although such sight adjustment is usually taken care of by the use of a vertically adjustable reticule mounted

5 in the telescope.

25

I have found that it is relatively impossible to effectively sight in or adjust a telescope sight in the usual or known types of mounts. That is to say it is relatively impossible to adjust these 30 mounts so that the shot group may be centered with any degree of certainty at the point of aim. This I attribute partly to the fact that the hunting type mounts as heretofore known have considerable looseness or backlash inherent in their 35 design and partly to the common practice of depending on friction between the parts of the mount for holding the mount in adjusted position. Not only is the usual hunting type of mount difficult to adjust but an accidental fall of the 40 rifle will often so disturb this adjustment that the rifle must be sighted in again.

In the preferred form of the invention to be 45 hereinafter described I follow to a certain extent the usual practice of attaching a plate to the receiver of the rifle and detachably supporting a mount base on the plate. I also prefer to make the mount adjustable vertically as well as laterally so as to eliminate the use of adjustable reticules which have always been troublesome. An 50 important feature of my invention resides in an arrangement for effecting positive movements of adjustment either laterally or vertically or both so that the point of impact of the rifle may be corrected or controlled in a manner heretofore 55 impossible. A further feature of the invention

resides in an arrangement for effecting these adjustments such that backlash, spring or the like are constantly eliminated as the mount is adjusted either laterally or vertically and without the necessity of adjusting any additional part or parts. 5 A still further feature resides in a novel arrangement for detachably supporting the mount base on the plate such that the use of dovetails or the like is eliminated the base being readily removed and replaced without disturbing the adjustment 10 of the telescope sight.

To these and other ends, the invention consists in the novel features and combinations of parts to be hereinafter described and claimed.

In the drawing,

Fig. 1 is an elevational view of a telescope sight mounting embodying the invention;

Fig. 2 is an end view of the same;

Fig. 3 is a sectional view along line 3—3 of Fig. 2;

Fig. 4 is a sectional view along line 4—4 of Fig. 1; and

Fig. 5 is a sectional view along line 5—5 of Fig. 1.

In the preferred embodiment of the invention 25 I have provided for both lateral and vertical movements of the telescope sight but it will be understood that I may use either of these alone. For example in cases where a telescope having a vertically movable reticule is used the vertical 30 adjustment of the mount may be dispensed with. Furthermore it is to be understood that the mount of the invention is not limited to use with any particular type of rifle and while shown and hereinafter described in connection with a bolt action 35 rifle it is capable of use with other types of repeating rifles as well as with single shot rifles.

In the drawing the reference numeral 10 indicates in general a bolt action rifle, which is broken away at the ends, rifle 10 having a receiver 11 40 on one side of which a plate 12 of telescope sight mount 13 is secured by suitable means, as for example, screws 14 the inside surface of the plate 12 being curved, as at 15, to fit the receiver 11, the plate being on the left side of the receiver 45 when looking towards the muzzle of the rifle. The base 16, of mount 13, is divided into an upper section 17, having clamping rings 18 and 19 for telescope 20, and a lower section 21 having a downwardly directed longitudinal slot 22 in which the 50 upper end of plate 12, fits plate 12 being detachably secured to the lower base section 21 by pivot screw 23.

Lower base section 21 is provided with a flat upper face 24 on which the flat lower face 25 55

of upper base section 17 rests the two sections being held against separation by screws 26 which pass through enlarged openings 27 in lower base section 21 at the ends thereof and are threaded in upper base section 17. A dowel 28, fast in one section and free in the other, serves as a pivot, about which the upper base section 17 may be swung on the lower base section 21, to provide for lateral or windage adjustments of the telescope 20, the enlarged opening 27 allowing sufficient lateral movement of screws 26 with respect to base section 21 to take care of any possible lateral or windage correction required.

Movement of upper section 17 about dowel 28 is produced by screws 29 and 30 which bear against studs 31 and 32 fast in upper section 17 and extending downwardly into enlarged openings 33 and 34 in lower section 21. The studs 31 and 32 are near the opposite ends of upper base section 17 and it will be readily understood that if one screw is loosened or backed away from its cooperating stud and the other screw tightened or forced against its stud the upper base section will be swung about the dowel 28 in a direction depending on which screw is loosened and which tightened. In practice the first screw is only loosened or backed up an amount sufficient to take care of the adjustment required and the other screw tightened an amount sufficient to force the cooperating stud against the end of the screw which was loosened. Thus as the adjustment is completed both screws will be bearing rigidly against their studs and, as the studs are at opposite sides of the dowel 28, the upper base section will be locked against movement about dowel 28 on the lower section 21. If desired the screws 26 may then be set up tighter to still further hold the base sections against relative movement.

Vertical movement of the telescope 20 is accomplished by screws 35 and 36 which pass through enlarged openings 37 and 38 in upper base section 17 and are threaded through lower base section 21 the screws 35 and 36 engaging the upper face 39 of plate 12 at the opposite ends thereof. It will be readily seen that if one of the screws 35 and 36 is loosened or backed up and the other tightened the base sections of the mount will be swung about the pivot screw 23 to elevate or depress the telescope 20. As in the case of the windage or lateral adjusting screws 29 and 30 the elevation screws 35 and 36, depending on which way the mount is to be swung, are only loosened or backed up an amount sufficient for the adjustment of telescope 20 necessary and the other screw tightened to swing the mount enough to force the end of the loosened screw against the plate 12. It will thus be apparent, as in the case of the windage screws, that upon the adjustment of the elevation screws 35 and 36 the mount will be locked rigidly against movement on pivot screw 23 by screws 35 and 36 bearing against the opposite ends of the plate.

The plate 12 fits tightly in slot 22 without any side play therein but not so tightly that the mount cannot be separated from the plate readily when the pivot screw is removed. In order to lock screws 35 and 36 against movement, and thus to keep the elevation adjustment from changing when the mount is separated from the plate, set screws 40 are provided mounted in section 21 and bearing against screws 35 and 36. The heads of screws 29, 30, 35 and 36 may be graduated, as at 41 and 42, to assist in making corrections in adjustment and if desired the pivot

screw 23 may be tapered, as at 43, and the opening in which screw 23 passes through plate 12 may be given a similar taper. Thus after the mount has been adjusted and removed from the rifle and again assembled thereon the tapered portion of the pivot screw 23 will assist in drawing the elevation screws into contact with the plate with the same degree of pressure that these screws had before removal.

In use the plate 12 is rigidly attached to the rifle or other firearm and the telescope rigidly clamped in rings 18 and 19 screws 44 being provided for this purpose. The plate thereafter remains permanently attached to the rifle and the telescope remains permanently clamped in the rings. Upon firing the rifle at a target it may become apparent that corrections of sight adjustment are necessary which may be made by adjusting the windage screws 29 and 30 if lateral correction is necessary or the elevation screws 20 35 and 36 if elevation corrections are necessary. When these adjustments have been made in the manner previously described the set screws 40 may set up as well as screws 26. All parts of the mount are now rigidly held against movement and the rifle may be fired indefinitely without further adjustments. Furthermore the mount may be removed from the plate and restored thereon without the necessity of readjusting the same. The lateral and vertical adjusting means take up all backlash and spring in the mount and thus it is impossible for an accidental blow on the telescope or mount to change the adjustment thereof.

While I have shown and described a preferred embodiment of my invention it will be understood that the same is not to be limited to all the details shown but is capable of variation and modification within the spirit of the invention and scope of the appended claims.

What I claim is:

1. In a telescope sight mount, a plate adapted to be attached to the receiver of a rifle, a base, means on said base for supporting a telescope sight, freely removable pivotal means for detachably supporting said base on said plate and means carried by said base and engaging said plate to swing the base about said pivotal means, said last named means and said base being freely separable from said plate as a unit upon removal of said pivotal means.

2. In a telescope sight mount, a plate adapted to be attached to the receiver of a rifle, a base having a slot in which said plate may be received, means on said base for supporting a telescope sight, freely removable pivotal means for detachably supporting said base on said plate with the latter in said slot, and means carried by said base and extending into said slot to engage said plate to swing the base about said pivotal means, said base and the means carried by the base for swinging the same being freely separable from said plate as a unit upon removal of said pivotal means.

3. In a telescope sight mount, a plate adapted to be attached to the receiver of a rifle, a base having a downwardly directed slot in which said plate is received, means on said base engaging said plate to pivotally support the base thereon, means on said base extending into said slot to engage said plate near one end thereof to swing said base in one direction and separate means extending into said slot on the side of said pivot opposite the first means to engage said plate to swing said base in the opposite direction, said

- means for swinging the base limiting the movement of one another.
4. In a telescope sight mount, a plate adapted to be attached to a rifle, a base having a slot in which said base is received, means for pivotally and detachably supporting said plate in said slot, a screw threaded in said base and extending into said slot to engage the plate to swing the base in one direction and a screw threaded in the base 10 and extending into the slot to engage the plate to swing the base in the opposite direction.
5. In a telescope sight mount, a base divided horizontally into two parts, one of said parts being provided with means for supporting a telescope sight, the other part having means associated therewith for attachment to a rifle, a vertical pivot associated with said parts about which one of the parts may swing horizontally, means fixed on one of said parts at the opposite ends 15 thereof and extending into the other part and adjustable means on the latter near the ends thereof adapted to engage said fixed parts to swing the first part about the pivot in opposite directions respectively.
- 25 6. In a telescope sight mount, a base divided horizontally into two parts having relatively flat opposing faces, means at either end of said parts for holding the faces against separation while permitting relative transverse movement, means mid way the length of the parts for joining them for relative pivotal movement about a vertical axis and means at the ends of one of said parts engaging the other part to swing the latter about the pivotal means in either direction.
- 35 7. In a telescope sight mount, a base divided horizontally into two parts, one of said parts being provided with means for supporting a telescope sight, the other of said parts having means associated therewith for attachment to a rifle, means associated with said parts for supporting them for relative pivotal movement about a vertical axis, studs on one of said parts near the opposite ends thereof and adjustable means on the other part engaging the studs for swinging the first part about the pivotal means.
- 40 8. In a telescope sight mount, a base divided horizontally into two parts, means on the upper part for supporting a telescope sight, means associated with the lower part for attachment to a rifle, a vertical dowel extending from one of said parts into the other mid way the length of said parts, said dowel serving as a pivot about which the upper part may swing horizontally on the lower, studs one at each of the ends of the upper 45 part and extending into the lower part, the lower part being provided with enlarged openings into which the studs extend and screws in the lower part extending into said openings to engage the studs to swing the upper part about the pivot.
- 50 9. In a telescope sight mount, a base divided horizontally into two parts, means on the upper part for supporting a telescope sight, means associated with the lower part for attachment to a rifle, a vertical dowel extending from one of said parts into the other mid way the length of said parts, said dowel serving as a pivot about which the upper part may swing horizontally on the lower, studs one at each of the ends of the upper 55 part and extending into the lower part, the lower part being provided with enlarged openings into which the studs extend and screws in the lower part extending into said openings to engage the studs to swing the upper part about the pivot.
- 60 10. In a telescope sight mount, a base on which a telescope may be mounted and means for detachably supporting the base on a rifle, said last named means comprising a plate adapted to be attached to the rifle and a removable pivot screw extending through the base and plate in a horizontal direction, means associated with the base 10 and engaging the plate at opposite sides of the pivot screw for swinging the base about the pivot screw, said base being divided horizontally into an upper and a lower part, means for pivoting said parts for transverse relative movement, and 15 means carried by one of said parts and engaging the other of said parts at either end thereof for swinging the parts relatively about the pivoting means.
11. In a telescope sight mount, a plate adapted 20 to be attached to a rifle, a base, means for attaching a telescope to said base, pivotal means for detachably supporting the base on said plate, a screw threaded in said base and engaging the plate to swing the base in one direction about the 25 pivotal means and a screw threaded in the base and engaging the plate to swing the base in the opposite direction, the base with the telescope mounted thereon and the screws being separable from the plate as a unit upon removal of said 30 pivotal means.
12. In a telescope sight mount, a fixed element adapted to be permanently attached to a firearm and a telescope sight supporting element adapted to be detachably received on said fixed element, 40 said telescope sight supporting element comprising means for securing a telescope thereon, a pair of spaced downwardly extending legs forming therebetween a slot in which the fixed element may be received and a pair of adjustable abutments extending into the slot at a spaced interval from one another and adapted to engage the fixed element to control the angular relation between the elements and detachable means engaging the legs and fixed element to hold the 45 fixed element between the legs in such angular relation.
13. In a telescope sight mount, a plate adapted to be attached to a rifle, a base, means for attaching a telescope sight to said base, detachable 50 pivotal means for securing the base on the plate, a screw threaded in the base and engaging the plate to swing the base in one direction about the pivotal means, a screw threaded in the base and engaging the plate to swing the base in the 55 opposite direction, and means for locking the screws in adjusted position, the base with the telescope sight mounted thereon and the screws being separable from the plate as a unit upon removal of the pivotal means, the screws remaining locked against movement during separation of the base from the plate.

FREDERICK A. KUHN.
